UNITED STATES PATENT OFFICE.

THEODORE HUTNIKOW, OF BROOKLYN, NEW YORK.

DESIGN FOR AN ELECTRIC-LAMP-SHADE BRIDGE.

Application filed September 8, 1927. Serial No. 23,332. Term of patent 7 years.

To all whom it may concern:

Be it known that I, THEODORE HUTNIKOW, a citizen of Russia, residing at Brooklyn, in the county of Kings and State of New York, have invented a new, original, and ornamental Design for an Electric-Lamp-Shade Bridge, of which the following is a specification, reference being had to the accompanying drawing, forming part thereof, in which:

Figure 1 is a top view of an electric lamp

shade bridge showing six of the six-end stars on each of the six points of an electric lamp shade bridge of my new design.

Figure 2 is a side view of an electric lamp shade bridge, of my design.

I claim:

The ornamental design for an electric lamp shade bridge as shown and described.

THEODORE HUTNIKOW.
